(57) **CLAIM**

The ornamental design for a charger for smartphone or smartwatch, as shown and described.

DESCRIPTION

FIG. 1 is a perspective view of a charger for smartphone or smartwatch;

FIG. 2 is a front elevation thereof;

FIG. 3 is a rear elevation view thereof;

FIG. 4 is a right side view thereof, the left side view being a mirror image thereof;

FIG. 5 is a top plan view thereof; and,

FIG. 6 is a bottom plan view thereof.

The broken lines in FIG. 1 represent environmental subject matter which forms no part of the claimed design. The broken lines in FIGS. 2-5 represent portions of the article which form no part of the claimed design.
